ABSTRACT OF THE DISCLOSURE

Changing the relative angle during feeding of a web-like material to a processing location to enable processing thereof along a generally wave-form like pattern.

This invention relates generally to methods and apparatus for processing web-like materials and, more particularly, to methods and apparatus for processing web-like materials at a material processing location along a generally wave-form like pattern.

This invention is especially useful for the production of decorative patterns on textile or other sheet or web-like material utilizing thread as decorative embroidery either wholly on the material or as a decorative edge. However, the present invention is not limited to such use, and may be utilized for the production of decorative or wave-form like patterns which are not formed by using thread or which are formed by processing of substantially any web or sheet-like material.

The present invention may produce scalloped or decorative embroidery or applique formed of stitching along a wave-form like path wholly on a web or sheet-like material, at or adjacent an edge thereof or simultaneously with a cutting operation to define a scalloped or wave-form like edge decorated with applique or embroidery stitching. The present invention may further continuously produce such decorative scalloped embroidery or applique on elongated, relatively narrow webs of material for subsequent utilization in various and diverse fabrication operations.

Accordingly, it is a primary object of the present invention to provide methods and apparatus of the class described which are simple, economical, reliable and capable of high speed operation.

Another primary object of the present invention, in addition to the foregoing object, is to provide such methods and apparatus wherein a web of material is moved in an arcuate path during delivery to a processing location to provide a varying angle of attack therewith.

Yet another primary object of the present invention, in addition to each of the foregoing objects, is to provide such methods and apparatus wherein guide means for a web or sheet-like material is moved in an arcuate path about a processing location to provide a varying angle of attack of the web or sheet-like material therewith.

A further primary object of the present invention in addition to each of the foregoing objects, is to provide such methods and apparatus for enabling the formation of a scalloped embroidered wave-form like edge of exceptional uniformity and at a high rate.

A still further primary object of the present invention, in addition to each of the foregoing objects of the present invention, is to provide such methods and apparatus wherein the amplitude, frequency, period and configuration of waveform like decorative patterns, such as scalloped embroidery may be readily and easily varied.

A yet still further primary object of the present invention, in addition to each of the foregoing objects, is to

2

provide methods and apparatus of the class described capable of producing substantially any cyclic or repetitive wave-form like pattern.

Another and yet still further primary object of the present invention, in addition to each of the foregoing objects, is to provide such methods and apparatus wherein the web or sheet-like material may be fed to the processing location without snagging, bunching, slipping, or the like.

Yet further, it is still another primary object of the present invention, in addition to each of the foregoing objects, to provide methods and apparatus of the class described for forming zig-zag or overedge stitching in a wave-form like pattern with each such stitch being generally perpendicular to the path of the pattern.

The invention resides in the combination, construction, arrangement and disposition of the various component parts and elements incorporated in improved apparatus for providing relative feeding movement between a web or sheet-like material and a work processing location and

in the methods involved therein. The present invention will be better understood and objects and important features other than those specifically enumerated above will become apparent when consideration is given to the following details and description, which when taken in

conjunction with the annexed drawing describes, discloses, illustrates and shows a preferred embodiment or modification of the present invention and what is presently considered and believed to be the best mode of practicing the principles thereof. Other embodiments

or modifications may be suggested to those having the benefit of the teachings herein, and such other embodiments or modifications are intended to be reserved especially as they fall within the scope and spirit of the subjoined claims.

35 In the drawing:

FIG. 1 is a pictorial illustration of apparatus constructed in accordance with the principles of the present invention;

FIG. 2 is a top plan view of the apparatus of FIG. 1; and

40 FIG. 3 is a side elevational view taken along line 3—3 of FIG. 2.

With reference now to the drawing, there is shown and illustrated apparatus constructed in accordance with the principles of the present invention and designated generally by the reference character 10.

At the outset, it is to be expressly understood that while the present invention is herein shown and illustrated as applied to apparatus for cutting and over-edge stitching of an elongated web of textile material in a generally sinusoidal wave-like pattern, the present invention is also utilizable for the production of substantially any desired wave-like pattern, either continuous or discontinuous. For example, and without limitation, the present invention may produce a generally sinusoidal scalloping, saw-tooth scalloping, zig-zag scalloping, convex or concave curvilinear scalloping or substantially any combination thereof.

Further, the present invention is utilizable for the formation of elongated webs of material, as shown, either as an end product, as an intermediate product for sale or utilization in additional fabrication, for securement with a backing panel of material simultaneously with the formation thereof, or for direct application to panels, webs or sheets of material. Again, the foregoing is by way of example only, and without limitation. Yet further, the present invention is susceptible to use with stitch-forming equipment, as shown, or with substantially any other processing or fabrication equipment, such as, by way of example and without limitation, printing wheels, adhesive apparatus, cutting equipment, perforating equipment, forming equipment, or the like.

The apparatus 10 shown and illustrated comprises a

sewing head 12 and apparatus 14 positioned relative thereto, as by being structurally associated with support structure 16 which is structurally associated with the sewing head 12.

The sewing head 12 may be of substantially any desired construction and design such as is well known in the sewing machine art, and further description thereof is not deemed necessary, other than that the sewing head 12 may be driven, generally at a constant speed, although the speed thereof may be varied independently or in synchronization to the apparatus 14, by means of a drive belt 18. The sewing head 12 may comprise a needle 20 driven from the drive belt 18 in a well known stitch forming manner to produce, for example, a zig-zag or over-edge lock stitch, as indicated at 22 in FIG. 2. The sewing head 12 may further be provided with feed dogs 24 for feeding a web of fabric material 26 relative to the needle 20 and with cutting means, such as a knife edge 28 adjacent the needle 20 for severing the web of fabric 26 as it is moved therpast by the feed dogs 24. There may also be provided a presser foot 30 which acts upon the material 26 to hold the material against the bed 32 of the sewing head 12. The web of material 26 may, for example, be moved past the needle 20 in the direction of the arrow 34. The amount of the movement of the fabric 26 in the direction of the arrow 34 may be adjusted in a well known manner to have a predetermined correlation to the movement of the needle 20. Normally this adjustment is made for the purpose of setting desired spacing between the stitches 22. If desired, the correlation may be further automatically adjusted or modified with reference to the apparatus 14.

The apparatus 14 may comprise a stand member 36 structurally associated with the support structure 16. The stand member 36 may be structurally associated with a generally vertically extending shaft 38 which may be disposed generally vertically above the needle 20 of the sewing head 12. The shaft 38 may rotatably carry elongate bearing means, such as an upper bearing 40 and a lower bearing 42 which may be disposed for rotation above the shaft 38 while being secured thereon against vertical movement relative thereto. Material guiding means 44 which may further provide tensioning of the material 26 may be structurally associated with the bearing means, as by an upper support rod 46 structurally associated with the upper and lower bearing 40 and 42 and a lower support rod 48 structurally associated with the upper support rod 46 and with the guiding means 44. The upper and lower support rods 46 and 48 may be adjustably interconnected, as by means of a clamp block device 50 to enable adjustment of the positioning of the guiding means 44 relative to the sewing head 12.

The guiding means 44 may be of any desired construction, depending upon the configuration and characteristics of the material 26 and, for an elongated generally narrow web of textile material or fabric the guiding means 44 may comprise a plurality of tensioning bars 52 about which the web of fabric material 26 may be passed in a serpentine manner. The tensioning bars 52 may be fabricated of either a resilient or a non-resilient material, and may be provided with a smooth or a high friction surface, depending upon the characteristics and requirements of the web of fabric or material 26.

The web of fabric or material 26 may be provided in the form of a roll 54. Accordingly, the apparatus 14 may further comprise a spindle rod 56 structurally associated with the support rods 46 and 48, as by means of the clamp block device 50 for rotatably supporting the roll 54. The spindle rod 56 may be provided with means for retaining the roll 54 thereon, and for tensioning the roll 54 against rotation. Such retaining and tensioning means may, for example, comprise an annularly extending shoulder 58 adapted to engage the roll 54 at one side thereof, an annular disk 60 to engage the other side of the roll 54, a tensioning spring 62 and a nut 64. The spindle rod 56 may be provided with threads 66 at least adjacent the out-

board end thereof to engage the nut 64. Accordingly, the roll 54 and the guiding means 44 may simultaneously oscillate or move in a generally arcuate path about the shaft 38. As hereinbefore pointed out, the shaft 38 may be generally vertically disposed above the needle 20 and hence, the roll 54 and the guiding means 44 may therefore oscillate or move in a generally arcuate path about the needle 20 to thereby vary the relative angle therebetween, or the angle of attack of the material 26 to the needle 20 which, it will be understood, defines the processing location.

Drive means, such as a variable speed motor 68, reduction gear means 70 and oscillatory drive means 71 may be structurally associated with the stand member 36. The oscillatory drive means 71 may be constructed and arranged to provide either uniformly or non-uniformly, continuously or discontinuously oscillatory movement for the guiding means 44. For example, and without limitation, the oscillatory drive means 71 may comprise eccentric drive means, comprising, for example a driving link 72, a drive pin 74 and a driven link 76 operatively associated with the output shaft 78 of the reduction gear means 70 and the bearing means 40 and 42, respectively, to provide for oscillatory, rotary drive of the bearing means 40 and 42 about the shaft 38 and, in turn, oscillatory circular movement of the guiding means 44 in an arcuate path about the shaft 38 and processing location as defined by the needle 20.

The driving link 72, which may be of generally elongate configuration, may be structurally associated, at one end portion thereof to the output shaft 78. The drive pin 74 may, as hereinafter described, be adjustably associated with the driving link 72 in spaced apart relationship to the output shaft 78. The driven link 76 may likewise be of generally elongated configuration, with one end portion thereof being structurally associated with the bearing means, as by being structurally associated with the upper bearing 40. The driven link 76 may be provided with an elongated generally longitudinally extending slot 80 adapted to be engaged by the drive pin 74. Accordingly, upon rotation of the driving link 72, the drive pin 74 will be reciprocated within the slot 80 of the driven link 76 to oscillate the driven link 72, the bearings 40 and 42, the guiding means 44 and the web of material 26 about the shaft 38 and, accordingly, about the axis of the processing location defined by the needle 20 to change the angle of attack of the material 26 as it approaches the needle 20.

The drive pin 74 may be either fixed to the driving link 72, or rotatably mounted thereon. As hereinbefore mentioned, the drive pin 74 may be adjustably associated with the driving link 72, as by engagement through an elongated slot 82 provided in the driving link 72 and being capable of securing at any desired location relative to the slot 82 as by means of a nut 84, or the like. Accordingly, the amplitude of the oscillation of the bearings 40 and 42 and, accordingly, the roll 54 and guiding means 44 about the shaft 38 may be readily varied by varying the distance of the drive pin 74 from the output shaft 78 of the reduction gear means 70.

It is believed readily obvious that the oscillatory drive means 71 hereinabove described in detail will produce a generally sinusoidal arcuate oscillation of the material 26 about the processing location as defined by the shaft 38 and needle 20. It is to be expressly understood, however, that the present invention may provide oscillatory movements which are not sinusoidal and, in fact, may comprise substantially any desired wave-form, both continuous and discontinuous by appropriate modification of the driving link 72, drive pin 74 and driven link 76. It is believed obvious that the driving link 72, drive pin 74 and driven link 76 in actuality define a fixed radius cam and follower arrangement and, further, that substitution of a cam follower arrangement of other than a fixed radius configuration will result in the pro-

duction of a wave-form like pattern which is not sinusoidal and, in fact, may be of substantially any desired configuration.

The drive means for the output shaft 78, as hereinbefore pointed out, may be of the variable speed variety comprising mechanical variable or change speed gearing or drive means between the motor 68 and the output shaft 78, as by being incorporated within the reduction gearing 70 or the drive motor 68 may be of the variable speed variety, the speed of which may be controlled by a speed control 86 of any desired type connected with the motor 68 and with the source of electric power as by means of electric cables or wires 88 and 90, respectively. For example, the speed control 86 may comprise an electronic speed control of either the open end or feedback variety. It is believed readily obvious that variations of the speed of the motor 68 will produce variations in the period of the wave-like form pattern produced on the material 26 and that variations in the amplitude of the oscillations will produce variations in the amplitude or depth of the wave-form like pattern. Moreover, the speed control 86 may be automatically controlled or varied to produce yet further modifications to the wave-form like pattern. Yet still further, the processing apparatus or sewing head 12 may similarly be of a variable stitch variety and automatically controlled in relation to the apparatus 14 to provide yet further modifications, variations and variety to the wave-form like pattern produced.

The apparatus 10 shown and illustrated may be operated, accordingly, as follows: the sewing head 12 may be operated at the maximum sewing speed thereof and the motor 68 energized. As the sewing head 12 operates, the feed dogs 24 thereof would be effective to pull the web of material 26 from the roll 54 past the knife edge 28 and the needle 20. As the output shaft 78 rotates, the bearings 40 and 42, the roll 54 and guiding means 44 will be oscillated about the axis of the shaft 38 and, accordingly, about the axis of the processing location or needle 20, constantly changing the angle of attack of the web of material 26 relative to the sewing head 12 so that the needle 20 and the knife edge 24 will sever and decoratively embroider the severed edge of the web of material 26 to define an embroidered, scalloped, generally sinusoidal edge as the material passes through the sewing head 12. Since the angle of attack is constantly changing, the web of material will always be moving directly into the feed dogs 24 without any lateral movement therebetween being necessary. Moreover, the stitches formed by the sewing head 12 will always be generally perpendicular to the edge cut by the knife edge 28. Hence, the apparatus 10 may be operated at a maximum speed, without the feed dogs 24 snagging, bunching, or otherwise interfering with the transfer of the web of material through the sewing head 12 and the stitches 52 will be of maximum uniformity and aesthetic appeal.

It is to be understood that terminology such as "upper" and "lower," as used in the preceding description and in the subjoined claims, along with other similar directional terminology, is to be construed and interpreted in its normal and accepted sense. However, such terminology is not to be construed or interpreted in a limiting sense either in the preceding description or the subjoined claims, since the same is used merely to facilitate an understanding of, and to clearly set forth and particularly define the present invention.

While the invention has been described, disclosed, illustrated and shown in terms of embodiments or modifications which it has assumed in practice, the scope of the invention should not be deemed to be limited by the precise embodiments or modifications herein described, disclosed, illustrated or shown, such other embodiments or modifications as may be suggested to those having the benefit of the teachings herein being intended to be re-

served especially as they fall within the scope and spirit of the claims here appended.

What is claimed is:

1. Apparatus for continuously processing an elongated web of material comprising, in combination: means for processing the material at a specific location, means adjacent said processing location for feeding such web theretofast, means for guiding the material relative to said processing location and means for moving said guiding means along a generally arcuate path having its center substantially aligned with said location for automatically varying the angle of attack of such material as it approaches said location so that such processing will be performed along a varied path extending generally longitudinally of the web.
2. Apparatus defined in claim 1 wherein said processing means comprises a sewing machine having a reciprocating needle mounted for cyclic passage through said processing location and said feeding means comprises rectilinear feeding means for moving the web of material across the needle travel path.
3. Apparatus defined in claim 1 wherein said guiding means comprises supporting means for the web of material.
4. Apparatus defined in claim 3 wherein said moving means comprises oscillatory drive means for said guiding means.
5. Apparatus defined in claim 4 wherein said oscillatory drive means comprises offset crank means constructed and arranged to provide variable amplitude oscillation.
6. Apparatus defined in claim 4 further comprising variable speed drive means for said oscillating drive means.
7. Apparatus defined in claim 6 wherein said oscillatory drive means comprises adjustable crank means constructed and arranged to provide variable amplitude oscillation.
8. Apparatus defined in claim 3 wherein said arcuate path is disposed in a plane generally parallel the plane of movement of the web past said processing location.
9. In combination with a stitch forming machine, guiding apparatus comprising guiding means mounted for movement along an arcuate path having a center substantially aligned with the stitch forming location for varying the angle of attack of a web of sheet-like material as it approaches the stitch forming location.
10. Method of processing web or sheet-like material comprising, at least the steps of, feeding the material relative to a processing location, supporting the web at a location spaced apart from the processing location and moving the support along a generally arcuate path having a center in general alignment with the processing location to vary the angle of attack of said material as it approaches such processing location.
11. Method defined in claim 10 wherein said step of moving comprises, at least the step of, oscillating the support cyclically along the generally arcuate path.
12. Method defined in claim 11 further comprising, at least the additional step of, varying the rate of oscillation of the support to provide a variable period of oscillation.
13. Method defined in claim 10 further comprising forming stitches at said material processing location.
14. Method defined in claim 13 further comprising severing said material at said processing location.
15. Embroidery apparatus comprising, in combination: a sewing machine having a needle and rectilinear feeding means and tape supply means comprising, in turn, a shaft generally axially aligned with the needle movement, bearing means carried by said shaft for rotational movement thereabout, frame support means mounted with said bearing means for rotation therewith about said shaft, roll material support and guiding means mounted on said frame means, and means to oscillate the frame and guide means across the machine line of feed.

16. Apparatus for continuously processing an elongated web of material comprising, in combination: means for processing the material at a specific location, means adjacent said processing location for feeding such web theretofore, means for guiding the material relative to said processing location comprising, in turn, supporting means for the web of material and oscillatory drive means for moving said supporting means along a generally arcuate path about said processing location to vary the angle of attack of such material as it approaches said location so that processing will be performed along a varied path extending generally longitudinally of the web.

17. Apparatus defined in claim 16 further comprising roll material support means structurally associated with said bearing means.

18. Apparatus defined in claim 17 further comprising frame means mounted on and carried by said bearing means wherein said material support means and said roll support means are mounted on and carried by said bearing means for rotation therewith.

19. Apparatus defined in claim 16 wherein said shaft extends generally perpendicular the plane of movement of the web past said processing location.

20. In combination with a stitch forming machine, guiding apparatus comprising guiding means mounted for oscillation along an arcuate path about the stitching forming location, shaft means disposed in general alignment with said location and bearing means rotatably carried by said shaft means, said guiding means being mounted with said bearing means for rotation therewith about said shaft to vary the angle of attack of a web sheet-like material as it approaches the stitch forming location.

21. Combination defined in claim 20 further comprising oscillatory drive means for said bearing means.

22. Combination defined in claim 21 further comprising variable speed drive means for said oscillatory drive means.

23. Combination defined in claim 21 wherein said oscillatory drive means comprises an adjustable crank and slider mechanism.

24. Combination defined in claim 20 wherein the stitch forming machine comprises a needle mounted for periodic movement through the stitch forming location and means for feeding the web of material past said location across the path of travel of said needle and wherein said shaft is disposed generally perpendicular the plane of movement of the web past said location.

25. Combination defined in claim 24 further comprising roll material support means mounted with said guiding means for oscillatory movement therewith.
